UNITED STATES PATENT OFFICE.

MORITZ WEINSTEIN, OF ST. LOUIS, MISSOURI, ASSIGNOR OF ONE-HALF TO
MAX SPERLING, OF ST. LOUIS, MISSOURI.

BABY-BUGGY AND THE LIKE.

No. 857,696.

Specification of Letters Patent.

Patented June 25, 1907.

Application filed October 3, 1906. Serial No. 337,238.

To all whom it may concern:

Be it known that I, MORITZ WEINSTEIN, a subject of the King of Roumania, residing at the city of St. Louis, State of Missouri, 5 United States of America, have invented a new and useful Improvement in Baby-Buggies and the Like, of which the following is a specification, reference being had to the accompanying drawings, forming part of this specification, in which—

Figure 1 is a side elevational view of a baby buggy or go-cart showing my improvement applied thereon; Fig. 2 is a side elevational view of the running-gear of the buggy, showing the several positions of the front wheels; Fig. 3 is an enlarged detail view of one of the side brackets which support the shaft carrying the front wheels; Fig. 4 is an enlarged detail view, looking from the inside, of the bracket shown in Fig. 3, showing the said shaft in cross section and the spiral spring co-operating therewith; Fig. 5 is a detail front view of the parts shown in Figs. 3 and 4; Fig. 6 is an enlarged detail view of the locking and tripping lever and its co-operating parts; and Fig. 7 is a front view of the parts shown in Fig. 6.

This invention relates to a certain new and useful improvement in baby buggies and the like, the object being to provide means whereby, when the buggy is rolled or passes abruptly from a higher to a lower plane, such as from a pavement to the street, the carriage is prevented from tilting forwardly.

With this object in view, the invention consists in novel means whereby, when the buggy is rolled or passes abruptly from a higher to a lower plane, a frame carrying the front wheels is automatically operated, the front wheels lowered, and the body of the buggy prevented from tilting forwardly, means being also provided to lock the wheels in normal or elevated position; the invention also further consists in the novel construction, arrangement, and combination of the several parts, all as will hereinafter be described and afterward pointed out in the claims.

Referring to the accompanying drawings, 1 indicates the body of the buggy; 2 the supporting frame for the body of the buggy; 3 the rear wheels; and 4 the front wheels.

5 indicates bracket extensions secured to the forward ends of the supporting frame

members 2. The brackets 5 are formed 55 with perforations through which passes a shaft 6 having angular extensions 7 outside the brackets 5. The shaft extensions 7 are formed with stub shafts 8 upon which are mounted the front wheels 4.

9 indicates a cross-bar extending between the front supporting frame members 2.

10 indicates a sleeve or hub on the shaft 6 and secured thereon by set screws 11. Secured on the sleeve 10 is a notched disk 12. 65 13 indicates bracket members secured to the cross-bar 9 and loosely engaging at their other ends the sleeve 10, one on each side of said disk 12. Mounted on a cross-bolt 14 between the bracket members 13 is a lever 70 15 provided with a projection 16 adapted to co-operate with said notched disk 12. To the upper end of said lever is secured a coiled spring 17, the other end of said spring being attached to said cross-bar 9. The lower end 75 of said lever 15 carries a small wheel 18, the periphery of which is normally slightly above the tread of the carriage, as shown in Fig. 1.

The tips of the forward ends of the supporting frame members 2 are bent at right 80 angles, as at 19, and have attached thereto one end of a spiral spring 20, see Fig. 4. The opposite end of said spiral spring 20 is fastened to a sleeve 21, which sleeve is secured on the shaft 6 by means of a pin 22. 85 The sleeve 21 is preferably formed with a plurality of alining perforations and on the withdrawal of said pin 22 is free to rotate on said shaft 6, whereby the tension of said spring 20 may be varied or adjusted, for purposes here- 90 inafter described.

The tendency of the springs 20, one of which is on each side of the buggy, is at all times to rotate or rock the shaft 6 and extensions 7 and thereby throw the wheels 4 backwardly and thus elevate, due to the construction of the rocking frame 6, the front part of the body of the buggy, as shown in dotted lines in Fig. 2. The shaft 6 and wheels 4 are, however, locked or held in normal or elevated position, as shown in Fig. 1, by means of the projection 16 on lever 15 engaging the notch 12^a on the disk 12, the projection 16 being held to its engagement with said disk by means of the coiled spring 17, see particularly Figs. 1 and 6. Now, should the buggy be rolled or pass abruptly from a higher to a lower plane, as from a

pavement to a street, the front wheels will naturally first leave the higher plane, whereupon the wheel 18 will contact with, and be tripped by, the curbing, the projection 16 forced out of engagement with the disk 12, and the frame 6 and wheels 4, due to the springs 20, will fly downwardly and rearwardly, thereby elevating, or rather preserving in a level position, the front part of the 10 baby buggy. On flying rearwardly and downwardly, I do not bring the extensions 7 into a directly vertical position under the body of the buggy, but, by means of a guard plate 23 and stops 24, see Fig. 3, regulate the 15 backward throw of the extensions 7 and keep said extensions in an obliquely forward position, so that the tendency of the front wheels is to resume their normal or elevated position when the front and back wheels are again on 20 the same plane and the weight of the body of the buggy and carried infant is more evenly distributed. The tension of the springs 20 is normally adjusted, by means of the sleeves 21 and pins 22, to slightly over-balance the 25 weight of the carried infant, so that when the front and back wheels are again on the same plane, the weight of the buggy and carried infant will overcome the tension of springs 20 and force the wheels 4 back to normal position, when they are again locked by projection 16 on lever 15 engaging notch 12^a on disk 12. Should, however, the front wheels, on 30 the buggy reaching a level surface, not readily resume their normal position, only a slight pressure of the hand is required to accomplish this result.

In the backward rotation of the shaft 6 in throwing the front wheels rearwardly and downwardly under the body of the buggy, 40 the projection 16 on lever 15 will drag over the notches 12^b on the disk 12, as said disk 12 rotates with said shaft 6, and thus said notches 12^b serve to retard or cushion the backward throw of the wheels and prevent 45 jarring. The length of the extensions 7 is regulated according to the particular construction of buggy or wagon involved. For baby buggies, in large cities, the extensions 7 would be made of slightly greater length than 50 the height of the curbing, as is obvious. Due to the novel construction of the frame 6, the front wheels are projected forwardly, thus giving the buggy a broader base than is usual in these constructions and thus lessening the 55 liability of the buggy overturning.

In rolling the buggy from a lower to a higher plane, as the carriage is usually tilted upwardly in front to raise the front wheels, the lever 15 is not generally tripped; but 60 should the lever 15 be tripped by the curbing or other projection, the effect would only be a further tilting upwardly of the front of the buggy; but in such case, there is practically no danger of the infant falling from the 65 buggy, as both the back of the carriage and

the person rolling the carriage are present to prevent the infant from falling out of the rear of the carriage. The main danger generally in these constructions is the liability of the infant falling out the front of the carriage 70 on passing from a higher to a lower plane, and this danger is obviated by my invention and without necessitating the buggy being bodily lifted on passing from a higher to a lower plane or without requiring the person 75 rolling the buggy coming from the rear to the front of the buggy. Should the front wheels be thrown downwardly and backwardly by the accidental tripping of the lever 15 from any cause, there would be no danger of the 80 infant falling from the buggy, as the said wheels would be swung backwardly and downwardly slowly, the buggy would be tilted backwardly—not forwardly where the danger of the infant falling from the buggy is 85 present—and the person rolling the carriage, being in the rear of the carriage, could easily prevent the infant falling from the buggy, as heretofore described.

While I have more particularly herein described my improvement as applied to a baby buggy, it is obvious that there are many other constructions to which my improvement could equally well be applied.

Having thus described my invention, what 95 I claim and desire to secure by Letters Patent is:

1. In a baby buggy or the like, the combination with the body thereof, of a running gear comprising rear and front wheels, said front wheels being depressibly mounted with relation to said body, and means for depressing said front wheels when the buggy is passing abruptly from a higher to a lower plane, said depressing means being adapted to be 105 automatically operated to depress said front wheels when said buggy is passing abruptly from a higher to a lower plane; substantially as described.

2. In a baby buggy or the like, the combination with the body thereof, of a running gear comprising rear and front wheels, said front wheels being depressibly mounted with relation to said body, means for depressing said front wheels, means for locking said 110 front wheels in normal position against the action of said depressing means, and means adapted to automatically release said locking means when the buggy is passing from a higher to a lower plane over an abrupt descent; substantially as described.

3. In a baby buggy or the like, the combination with the body thereof, of an under-frame, rear wheels on said underframe, front wheels depressibly mounted on said under-frame, means tending to depress said front wheels at all times, means for locking said front wheels in normal position against the action of said depressing means, and means adapted to automatically release said locking 125 means.

means when the buggy is passing abruptly from a higher to a lower plane; substantially as described.

4. In a buggy or the like, the combination with the underframe, of a depressible frame carried thereby, means for holding said frame in normal elevated position, and means, acting in opposition to said holding means, for depressing said frame, said holding means being adapted to be automatically released when said buggy passes over an abrupt descent; substantially as described.

5. In a buggy or the like, the combination with an underframe, of a rotatable frame carried thereon, wheels on said frame, means for locking said frame in normal position, and coiled springs mounted on said frame for rotating said frame when said locking means is released; substantially as described.

20 6. In a buggy or the like, the combination with an underframe, of a rotatable frame carried thereon, wheels on said frame, means for locking said frame in normal position, springs adapted to rotate said frame when said locking means is released, and means for regulating the amount of rotation of said frame when said locking means is released; substantially as described.

30 7. In a buggy or the like, the combination with the underframe, of a rocking frame carried thereby, wheels on said rocking frame, a spring actuated lever and notched disk for locking said frame in normal position, and springs adapted to automatically rock said frame rearwardly when said lever is tripped out of engagement with said disk; substantially as described.

45 8. In a buggy or the like, the combination with the underframe, of a rocking frame carried thereby, wheels on said rocking frame, means for locking said frame in normal position, means for swinging said frame rearwardly when said locking means is released, and means for cushioning the rearward swing of said frame; substantially as described.

9. In a buggy or the like, the combination with the underframe, of a depressible frame carried thereby, automatically releasable means for holding said frame in normal elevated position, and means for depressing said frame when said holding means is released; substantially as described.

55 10. In a buggy or the like, the combination with the underframe, of a rocking frame carried thereby, wheels on said rocking frame, automatically releasable means for holding said rocking frame in normal elevated position, and means for rocking said rocking frame and its carried wheels when said holding means is released; substantially as described.

65 11. In a buggy or the like, the combination with the underframe, of a rocking frame carried thereby, wheels on said rocking

frame, an automatically releasable locking lever mounted on said underframe and adapted to co-operate with said rocking frame for holding the same in normal elevated position, and a spring connected to 70 said rocking frame, the tension thereof being exerted, in opposition to said locking lever, to rock said frame, whereby, when said locking lever is released from co-operation with said rocking frame, said spring will rock said 75 frame and its carried wheels; substantially as described.

12. In a buggy or the like, the combination with the body thereof, of a running gear comprising a frame, rear wheels mounted on 80 said frame, a rocking frame mounted on said first-mentioned frame, front wheels mounted on said rocking frame, a notched disk on said rocking frame, an automatically releasable locking lever mounted on said first-mentioned frame and adapted to co-operate with said disk to lock said rocking frame in elevated normal position, and a spring for rocking said frame when said lever is in inoperative position with respect to said disk; substantially as described.

13. In a buggy or the like, the combination with the underframe, of a rotatable shaft, extensions on said shaft, wheels on 95 said extensions, means attached to said shaft for rotating the same, means mounted on said underframe and co-operating with said shaft for normally holding the said extensions in elevated position against the action of said rotating means, and means for regulating the rotation of said shaft when said locking means is in inoperative position; substantially as described.

14. In a buggy or the like, the combination with the underframe, of a rotatable shaft 105 on said frame, extensions on said shaft, wheels on said extensions, a notched disk on said shaft, a spring actuated lever mounted on said underframe and adapted to co-operate with said disk to lock said shaft against 110 rotation, and springs on said shaft for rotating the same when said lever and disk are disengaged; substantially as described.

15. In a buggy or the like, the combination with the underframe, of a rocking shaft 115 on said frame, extensions on said shaft, wheels on said extensions, a notched disk on said shaft, a spring-actuated lever mounted on said underframe and adapted to co-operate with said disk to lock said shaft against 120 rocking movement, springs on said shaft for rocking the same when said lever and disk are disengaged, and means for regulating the tension of said springs; substantially as described.

16. In a buggy or the like, the combination with the underframe, of a rotatable shaft 125 on said underframe, extensions on said shaft, wheels on said extensions, means for locking said shaft against rotation, in which locked 130

position said wheels are presented forwardly of said underframe, and springs for rotating said shaft when said locking means is released, the rotation of said shaft swinging said wheels backwardly and downwardly under said body; substantially as described.

17. In a buggy or the like, the combination with the underframe, of a tilting frame mounted thereon, said frame consisting of a shaft, extensions on said shafts, and wheels on said extensions, a notched disk on said shaft, a spring-actuated lever co-operating with said disk and when in engagement therewith locking said wheels in a forward, elevated position, springs on said shaft adapted to swing said wheels downwardly and rearwardly when said lever is disengaged from said disk, and means acting in opposition to said springs for regulating the rearward and downward swing of said wheels when said lever is disengaged from said disk; substantially as described.

18. In a buggy or the like, the combination with the underframe, of a tilting frame

mounted thereon, said frame consisting of a shaft, extensions on said shafts, and wheels on said extensions, a notched disk on said shaft, a spring-actuated lever co-operating with said disk and when in engagement therewith locking said wheels in a forward, elevated position, springs on said shaft adapted to swing said wheels downwardly and rearwardly under said buggy when said lever is disengaged from said disk, stops for regulating the amount of the downward and rearward swing of said wheels when said lever is disengaged from said disk, and means for cushioning the downward and rearward swing of said wheels; substantially as described.

In testimony whereof, I have signed my name to this specification in the presence of two subscribing witnesses.

MORITZ WEINSTEIN.
